THERMORESPONSIVE SWITCH MEANS

Robert J. Cassidy, Mansfield, Ohio, assignor to Pace, Inc.,
Mansfield, Ohio, a corporation of Ohio

Application September 10, 1954, Serial No. 455,174

11 Claims. (Cl. 200—139)

This invention relates to switch mechanisms and more especially to adjustable switch mechanisms embodying thermo-responsive means for maintaining automatic control of a circuit of a heating means or heating unit.

Switch mechanisms embodying thermoresponsive means for controlling the temperature of heating elements have heretofore incorporated an insulating means associated with the thermoresponsive means engageable with a switch arm or contact-carrying strip, such arrangement controlling an electrical circuit through the flexure or relative movement of a thermoresponsive element caused by variations in temperature. It has been conventional practice to utilize a pin or member formed of ceramic, lava or other suitable high temperature resistant material permanently secured to the thermoresponsive means and adapted for engagement with a contact-carrying strip. The insulating member has heretofore been formed with an annular kerf or groove, and the thermoresponsive means in the form of a bimetallic strip or element has been provided with a recess for receiving the button and wherein adjacent portions of the bimetal element are distorted or bent into the kerf or groove to hold the element and member in assembled relation. The prior methods of securing the member formed of ceramic or lava to a bimetal element involve swaging or distorting the metal of the element into the kerf in the element, and this operation affects the thermoresponsive characteristics of the bimetal element, impairing the accuracy of its functioning. Furthermore, as temperature variations adjacent the bimetal element cause expansion and contraction of the element, the member of insulating material becomes loosened after a comparatively short period of operation. Such lost motion or looseness causes the operation of the bimetal element to become unstable and unreliable for controlling the operation of the switch mechanism at a selected temperature.

The present invention has for an object the provision of a novel method and means of connecting a member of insulating material with a thermoresponsive means so as to secure efficient and reliable functioning of the thermoresponsive means.

An object of the invention is the provision of a means for connecting a member of high temperature resistant insulating material with a bimetallic element through the medium of a securing means engageable with the insulating member and the bimetallic element in a manner to reliably hold the parts in assembled relation without any looseness or lost motion and providing a means which will hold the parts together when subjected to variations in temperature without impairing the rigidity of the connection.

Another object of the invention resides in a method of securing an insulating member of high temperature resistant material to a bimetallic unit wherein the insulating member extends through an opening in the bimetallic unit and a retaining member engaged with the insulating member and the bimetallic element, this arrangement providing a rigid connection between the bi-

2

metallic element and insulating member which will not become dislodged or impaired over long periods of use.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is an enlarged side elevational view of a thermostat switch construction embodying a form of the invention;

Figure 2 is an enlarged end view of a portion of the construction shown in Figure 1;

Figure 3 is a view taken substantially on the line 3—3 of Figure 2;

Figure 4 is a bottom plan view of the construction shown in Figure 3;

Figure 5 is a greatly enlarged view of securing means forming part of the invention;

Figure 6 is an enlarged detail sectional view taken substantially on the line 6—6 of Figure 2, and

Figure 7 is a view similar to Figure 6 illustrating a step in the method of applying an insulating member securing means to the bimetal element.

While the arrangement of the invention is illustrated as utilized in a thermostat switch construction for use with electrical appliances, it is to be understood that the arrangement of the invention may be used with any mechanism wherein the same may be found to be applicable.

Referring to the drawings in detail, there is illustrated in Figure 1 a portion 10 of an electrical appliance such, for example, as an electric iron provided with a heating element 12 to which electrical energy is supplied through supply conductors or lines L1 and L2. The portion 10 of the appliance provides a support for a switch mechanism which is both manually and thermostatically controlled. The switch construction is shown enlarged to about twice actual size and is inclusive of a plate or member 16 upon which is mounted a member or sleeve 18 provided with a tenon 20 which fits into an opening formed in the plate 16 and is swaged or staked as at 22 to fixedly secure the sleeve 18 to the plate 16.

The interior of the sleeve 18 is threaded to receive a threaded portion 24 of a member 25 forming an element of the manual control means for the switch mechanism. Secured to member 25 is an arm 27 provided with a finger piece 28 for manipulating or rotating the arm 27 and member 25 relative to the sleeve 18 for adjusting the position of a contact-carrying switch member or flexible strip 30. The member 25 is interiorly bored and threaded to receive a member 32, provided with a kerf 33 to facilitate rotation of member 32 with respect to member 25

55 to secure initial adjustment of member 32 for a purpose hereinafter described. The lower end of member 32 is formed with a socket 34 to receive the upper end of a pin 36 formed of ceramic, lava or other high temperature resistant insulating material. The lower end of the pin 36 is fashioned to a generally wedge-like shape 37 which is received in a generally rectangularly shaped opening or depression formed in the switch member 30. The switch member 30 is provided with a contact 39 which is arranged for cooperation with a contact 41 carried by a

60 second switch member or flexible strip 42. The pin 36 extends through a clearance opening 43 in the uppermost switch member 42.

A thermoresponsive means in the form of a bimetallic element 45, comprising two dissimilar metals having different coefficients of expansion, is disposed coincident with a portion of the appliance 10 so as to be directly subjected to and influenced by heat generated by resistance

to the passage of an electric current through the heating element 12. An extremity of the bimetallic element 45 is provided with an insulating member 48 which is secured to the bimetallic element in a manner hereinafter described. The insulating element 48 is adapted for engagement with the flexible switch member 42 for a purpose hereinafter explained.

Means is provided for securing the switch arms or flexible strips 30 and 42 and the bimetallic element 45 in predetermined relation as a unit as illustrated in Figure 1. 10 A metal member 50 of disk-like configuration is formed with an upwardly extending, thin-walled sleeve portion 52 which extends through an opening in the plate 16, and after assembly of the bimetallic element 45, switch members 30 and 42 and insulating washers, the upper end of 15 the sleeve is swaged or spun to a configuration shown at 54. The bimetallic element 45 has an opening to receive the sleeve 52 and is insulatingly supported from the sleeve by means of an insulating washer 55.

The flexible switch member 30 and an adjacent connector or terminal member 57 are provided with openings which receive tenons formed on a washer 58 of insulating material, whereby the member 30 and terminal 57 are insulatingly supported upon the sleeve 52. The switch member 42 and a second terminal 60 in contact therewith are formed with registering openings to receive a tenon formed on a washer 62 of insulating material whereby the switch member 42 and connector 60 are also carried by and insulated from the sleeve 52. Through the provision of members 55, 58 and 62 the current-conducting terminals 57 and 60 and the flexible strips forming switch members 30 and 42 are insulated from the other components of the switch construction.

The terminals 57 and 60 are adapted to be connected respectively with the current supply conductor L1 and a conductor L3. The supply conductor L2 and conductor L3 are connected with the heating element 12 of the appliance. The switch assembly may be mounted upon the appliance 10 through the use of a bolt 64 extending through the sleeve 52 of the disk-like member 50 and into a threaded opening 66 formed in the appliance 10.

The arrangement of the present invention includes a novel means for securing the insulating member or button 48 to the end zone of the bimetallic member 45. The button or pin 48 formed of ceramic or lava is provided with a head 70. The end zone of the bimetallic element 45 is provided with a circular opening 72 which is of slightly larger diameter than that of the body portion 49 of pin 48 and is adapted to receive the body of the pin as particularly shown in Figures 2, 3, 6 and 7, the head 70 engaging the lower surface of the bimetallic element 45.

Means is provided for fixedly securing the pin or button 48 to the bimetallic member 45. The form of means illustrated is a fastener, clip or locking member which is illustrated in the enlarged view of Figure 5. The clip or locking member 75 is formed of sheet metal such as stainless steel or the like tempered to provide a degree of resiliency or flexibility so that the inherent resiliency in the clip functions to hold the button 48 in position. The clip 75 is formed with a body portion 77 having transversely extending ear portions 79 which are fashioned to U-shaped configuration as shown in Figure 5. One edge zone of the body portion 77 is formed with a struck-up or bent-up lug or abutment portion 80. The body portion 77 is also fashioned with a raised portion 82, preferably of spherical shape, which is adapted to engage the button substantially at the central zone thereof. As shown in Figure 3, the edges or edge zones of the bimetallic element 45 are tapered slightly in the direction toward the end thereof equipped with the button 48. The bight portions 84 of U-shaped projections 79 are provided with a similar taper as shown in Figure 3 so that in the assembly of the clip 75 with the bimetallic element 45, the edge zones of the latter will be engaged by the tapered surfaces of the bight portions 84.

Figure 6 illustrates the clip 75 in final assembled rela- 75

iton with the bimetal element 45 and the lava pin or button 48. Figure 7 illustrates a step in the method of assembling the clip 75 with the bimetal element and the button. In assembling the button and clip to the bimetallic element, the body or shank 49 of the button or pin 48 is inserted in the opening 72 in the bimetal element 45 with the head portion 70 in contiguous or engaging relation with the lower surface of the bimetallic element as shown in Figure 7. The clip 75 is slipped over the end zone of the bimetal element 45 with the body portion 77 adjacent the head portion 70 of the button and the U-shaped projections 79 overtaking or overlying the edge zones of the bimetallic element 45 as in the manner particularly shown in Figures 2, 3 and 4.

The clip 77 is advanced to the position shown in Figure 7 until the struck-up or raised portion 80 extends beyond the peripheral edge of the head portion 70 of button 48. The metal of the struck-up portion or abutment 80 is sufficiently resilient so that the abutment 80 is flexed as it is slidably moved across the head 70. In this position the raised portion 82 is in snug engagement with the central zone of the lower surface of the head 70. After the parts are in the position shown in Figure 7, the assembler then slides the retaining clip 75 in a right hand direction as viewed in Figure 7 to the position shown in Figure 6. In this position, the body portion 49 of the button 48 engages an outer edge wall of the opening 72 in the bimetallic element 45 defining the opening 72, the said portion of the edge wall serving as a positioning or abutment means for properly locating the button 48 with respect to the bimetal element shown in Figure 6. The clip 75 in its assembled position is disposed as shown in Figure 6 with the raised or struck-up portion 80 engaging a peripheral edge zone of the head 70, the arrangement serving to prevent dislodgement of the clip 75.

The inherent flexure in the clip 75 securely retains the button 48 in its proper position. Expansion or contraction of the elements is compensated by the resilient or flexible characteristics of the clip construction 75, and the clip is maintained in snug engagement with the bimetallic element 45.

In the event the button 48 becomes broken, necessitating repair or replacement, the clip 75 may be readily removed by bending or distorting the raised portion 80 downwardly out of contact with the head 70 of the button after which the clip may be slidably removed from the end zone of the bimetallic element 45.

The switch mechanism embodying the invention is especially usable for regulating the temperature of electrical appliances. In operation of the device, the terminals 57 and 60 are connected in series with the heating elements 12 which receive electrical energy from electrical energy supply lines L1 and L2. The bimetallic element or thermostat 45 is responsive to the heat generated by the passage of electrical energy through the resistance or heating units 12. The manual means 27 may be adjusted to a position predetermining the location of the contact 39 so that, upon flexure of the bimetallic element 45 set up by heat energy from the heater 12, the button or member 48 carried by the element 45 engages the flexible strip or switch arm 42 to elevate contact 41 and interrupt the circuit through the heating elements 12. By modifying the relative position of the contact 39 through the manually adjustable means 27, the temperature of the appliance and the temperature ambient the switch mechanism may be controlled. Through the present arrangement of means for securing the insulating member 48 to the bimetallic member or thermostat 45, the thermostat is free to respond to variations in temperature without affecting the securing means holding the member 48 to the thermostat. Furthermore, in event of damage to or breakage of the insulating member 48, the same may be removed and replaced by removing the clip 75.

The manually controlled means 27 is rotatable through

predetermined limits to adjust the position of the thermoresponsive element 45 for operation in a desired temperature range and cooperates with a scale or member (not shown) bearing calibrations indicating temperature settings for the appliance. The member 32 is threadedly connected with the sleeve 25 and is adapted to be rotated or adjusted to determine the temperature range of the manually operable means 27. The member 32 may be adjusted by means of a suitable tool inserted in the kerf 33 to move the switch member 30 within a desired working range of the thermoresponsive means 45. After the initial adjustment of member 32 has been completed, a cementitious or bonding material may be applied as shown in the drawings at 85 to prevent further rotation of member 32 relative to the sleeve 25. A resinous bonding material or solder may be utilized for the purpose. It is preferred to use a bonding material of a character permitting the bond to be readily broken or disrupted in the event it becomes necessary to readjust the relative position of the switch member 30.

It is apparent that, within the scope of the invention, modifications and different arrangements may be made other than is herein disclosed, and the present disclosure is illustrative merely, the invention comprehending all variations thereof.

I claim:

1. Apparatus of the character disclosed, in combination, switch means having flexible current-conducting members, a thermoresponsive means, an insulating member carried by said thermoresponsive means and arranged for engagement with one of said flexible current-conducting means for moving the latter upon variations in temperature, and a retaining member having portions engaging the thermoresponsive means and a centrally disposed raised portion engaging said insulating member for securing the insulating member to the thermoresponsive means.

2. Apparatus of the character disclosed, in combination, switch means having flexible current-conducting members, manually operable means for adjusting the relative position of one of said flexible current-conducting means, a thermoresponsive element, an insulating member carried by said thermoresponsive means and engageable with the other of said flexible current-conducting means for controlling the position of the latter upon ambient temperature changes, said insulating member having a portion extending through an opening in the thermoresponsive means and a head portion engaging a surface of thermoresponsive means, and a retaining member having means engaging the thermoresponsive means and the head portion of the insulating member for securing the insulating member to the thermoresponsive means.

3. Apparatus of the character disclosed, in combination, switch means having flexible current-conducting members, manually operable means for adjusting the relative position of one of said flexible current-conducting means, a thermoresponsive means having an opening therein, an insulating member carried by said thermoresponsive means and arranged for engagement with the other of said flexible current-conducting means for moving the latter under the influence of changes in temperature, said insulating member having a portion extending through the opening in the thermoresponsive means, said insulating member having a head portion, and a retaining member having portions engaging the thermoresponsive means and a raised projection engaging the head portion of said insulating member for securing the insulating member to the thermoresponsive means.

4. In combination, a support, a pair of switch members anchored to the support, said switch members having cooperating contacts, a bimetallic element anchored to the support, said bimetallic element having a circular opening formed therein, an insulating member formed with a body portion extending through the opening and

a head portion engaging a major surface of the element, said insulating member arranged to engage one of said switch members, and a retainer formed of sheet metal for holding said member to said element.

5. In combination, a support, a pair of switch members anchored to the support, said switch members having cooperating contacts, a bimetallic element anchored to the support, said bimetallic element having an opening formed therein, an insulating member formed with a portion extending through the opening and arranged to control the position of one of said switch members, said insulating member having an abutment engageable with the bimetallic element for positioning said member relative to said element, a retainer formed of sheet metal for holding said member to said element, said retainer having a struck up portion engageable with the abutment of the insulating member and projecting portions engaging and embracing edge zones of said bimetallic element for securing the insulating member against movement relative to said element.

6. In combination, a support, a pair of switch members anchored to the support, said switch members having cooperating contacts, a bimetallic element anchored to the support, said bimetallic element having an opening formed therein at a zone spaced from the support, an insulating member arranged to control the position of one of said switch members, said insulating member being formed with a shank portion extending through the opening, said insulating member having a head portion engageable with the bimetallic element for positioning said member relative to said element, a retainer formed of sheet metal for holding said member to said element, said retainer having a centrally disposed raised portion engageable with the head portion of the insulating member and U-shaped ear portions engaging the edge zones of said bimetallic element for securing the insulating member against movement relative to said element.

7. In combination, a support, a thermoresponsive means comprising a unit formed of dissimilar metals, said unit having an opening formed therein, a member formed of insulating material having a shank portion and an enlarged head portion, the shank portion adapted to extend through the opening in the unit and the head portion engaging the unit, and a clip formed of sheet metal having laterally opposed portions engaging the edge zones of the thermoresponsive means and a centrally disposed raised portion engaging the head portion of the insulating member for retaining the insulating member in the opening in said thermoresponsive unit.

8. In combination, a support, a thermoresponsive means formed of dissimilar metals, said thermoresponsive means having an opening formed therein, an insulating member having a shank portion and a head portion, the shank portion adapted to extend through the opening in the thermoresponsive means and the head portion to engage said means, a retainer securing the insulating member in the opening in said thermoresponsive means, said retainer having a portion engageable with the head portion of the insulating member and laterally opposed portions engaging the edge zones of the thermoresponsive means, said retainer having a raised tongue adapted to contact the peripheral zone of the head portion to resist displacement of the retainer.

9. In combination, a support, a thermoresponsive means formed of dissimilar metals, one end zone of the thermoresponsive means being anchored to the support, the opposite end zone of the thermoresponsive means having an opening formed therein, an insulating member having a shank portion and abutment formed thereon, the shank portion adapted to extend through the opening in the thermoresponsive means and the abutment to engage a surface of said means, a retainer securing the insulating member in the opening in said thermoresponsive means, said retainer being formed of sheet metal having a portion engageable with the abutment of the insulating

member and laterally opposed portions engaging the edges of the thermoresponsive means, said retainer having a struck-up portion adapted to contact the peripheral zone of the head portion to resist displacement of the retainer.

10. A method of assembling a member of insulating material to an elongated bimetallic element having an opening formed therein including the steps of inserting the member in the opening in the element, slidably moving a retainer along the element in one direction until a projection on the retainer is forced beyond the member, and sliding the retainer in the opposite direction whereby the projection carries the member into engaging relation with a wall of the opening of the element.

11. A method of assembling a headed insulating member to an elongated bimetallic element having an opening 15

formed therein including the steps of inserting the insulating member in the opening with the head engaging the element, slidably moving a retainer over an end zone of the element until flexible projection on the retainer is moved beyond the head of the member, and retracting the retainer in the opposite direction whereby the projection moves the member into engaging relation with a wall of the opening in the element.
